UNITED STATES PATENT OFFICE.

ANTHONY F. HAMMERSCHMIDT, OF GRAND RAPIDS, MICHIGAN.

METALLIC RAILWAY-TIE.

1,101,179.

Specification of Letters Patent. Patented June 23, 1914.

Application filed December 2, 1913. Serial No. 804,185.

To all whom it may concern:

Be it known that I, ANTHONY F. HAMMERSCHMIDT, a citizen of the United States, and residing at Grand Rapids, in the county 5 of Kent and State of Michigan, have invented certain new and useful Improvements in Metallic Railway-Ties, of which the following is a specification.

This invention relates to new and useful 10 improvements in railway ties and more particularly to those constructed of metal.

An object of this invention is the provision of a metal tie, which will have the elastic effect similar to that of the old wooden type.

15 Another object of this invention is the provision of a metal tie so constructed as to allow the rails to be laid at any angle, spaced as desired and furthermore to provide a good substantial locking means for 20 the rail, whereby the same will be held against displacement.

A still further object of this invention is the provision of a metal tie that can be readily assembled and taken apart by any 25 novice.

With the above and other objects in view, this invention resides in the novel features of construction, formation, combinations, and arrangements of parts to be hereinafter 30 more fully described, claimed and illustrated in the accompanying drawings, in which:—

Figure 1, is a side elevation of my metal tie, with rails in position, Fig. 2, is a top-plan view of my tie, with rails removed, 35 Fig. 3, is a longitudinal sectional view of the same, Fig. 4, is an end elevation, Fig. 5, is a top-plan fragmentary view of the springs and base plate, with top plates removed, Fig. 6, is a perspective view of the locking 40 key, Fig. 7, is a perspective view of the locking spring, and Fig. 8, is a fragmentary sectional view of the key and spring lock in position.

45 Referring to the accompanying drawings by similar characters of reference the numeral 10 denotes in general my improved metal tie, which consists of a base plate 11, arched springs 12, and rail-securing top 13. The base plate 11 has a channel 14, formed 50 in its lower face and running longitudinally of the same, the intermediate portion of this channel being slotted as at 15, while the outer ends are notched as at 16. Mounted upon the upper face of the base plate 11 are 55 two arched spring members 12, these springs terminating at their outer ends 17 into webs

18, while their inner ends 18' terminate into a series of small finger like webs and notches 19 and 20 so as to coöperate. Formed upon the lower face of the flanges 18 and upon those of the small finger like webs 21 and 22 are downwardly extending lugs 23, terminating into T heads 24, which slidably operate in the slot 15 and notched outer ends 16 of the base plate 11. 60

Formed upon the intermediate portion of the springs 12 are blocks 25, having transverse apertures 26, formed therein for the reception of the bolts 27 which securely hold the rail adjusting casing 28 in position. The 70

casing 28 is composed of two plates 29 and 30 having downwardly extending webs 31 and 32, formed thereon and which in turn have outwardly extended webs 33 and 34 formed thereon. These downwardly extending webs 31 and 32 have suitably spaced apertures 35 formed therein to coöperate with those of the blocks 25 and 36, the latter blocks being disposed between the webs 31 and 32 and serving to hold the plates 29 and 80 30 in spaced relation to each other, and also producing a longitudinal slot 37 therebetween. Formed in the plates 29 and 30 are key holes 38, the plate 29 having less in number than the opposite plate 30. The 85 key holes in both plates being so arranged that when the tie is in position for the laying of the rails, the holes will be at an angle to each other, thus permitting the rails to be laid at any desired angle as well as permitting them to be spaced as desired. 90

The key holes 38 are for the reception of keys 39 which are somewhat similar to the customary tie spike, owing to the similar construction of the head 40 and shank 41. 95 The shank 41 having vertical grooves 42 formed therein and terminating into a wing portion 43, similar to that of the ordinary door keys. The grooves 42 in the shank 41 being produced for the reception of a spring 100 lock 44, which has an off set portion 45 formed thereon to coöperate with one of the grooves 42, thus locking the keys 39 in a substantial position, which in turn assures a substantial locking means for the rails 46. 105 It should be understood in this connection, however, that various minor changes in the details of construction can be resorted to within the scope of the appended claims without departing from or sacrificing any of 110 the advantages of this invention.

From the foregoing disclosure taken in

connection with the accompanying drawings, it will be manifest that a metal railway tie is provided, to answer the purpose of a wooden tie in every respect, the arched springs giving the elastic effect similar to that of the wooden tie while the plates with the key holes formed therein for the reception of the keys and locking springs produce a perfect locking means for the rails, thus eliminating the use of the old style railway spike entirely, and also producing a railway tie upon which rails may be mounted at any angle and spaced as desired.

Having thus fully described this invention, what I claim as new and desire to protect by Letters Patent is:—

1. A metal railway tie having a channeled base, a series of springs mounted thereon, blocks formed upon the intermediate portions thereof, a casing secured thereto, and means for securing rails thereon.

2. A metal railway tie comprising a cas-

ing, springs supporting the same and having webs formed thereon with lugs formed therefrom and terminating into T heads 25 slidably operating in the said channeled base, and means for securing rails to the said casing.

3. A metal railway tie having a flat top, a slot formed therein, webs extending downwardly therefrom, and having apertures formed therein, webs thence extending outwardly therefrom, blocks disposed between the downwardly extending webs and having transverse apertures formed therein, means 35 for suitably adjusting rails to the flat top and a channeled base supporting the same.

In testimony whereof I affix my signature in presence of two witnesses.

ANTHONY F. HAMMERSCHMIDT.
